SHIPPING CONTAINER

Joseph B. Arbuthnot, Brentwood, Pa.

Application November 14, 1942, Serial No. 465,594

2 Claims. (Cl. 229—23)

This invention relates to new and useful improvements in packing cases or shipping containers, and it is among the objects thereof to provide a container of corrugated cardboard or similar lightweight material which shall be inexpensive and rugged and so constructed that the portion thereof which is the base for assembly and packing constitutes the lid or cover.

It is a further object of the invention to provide a shipping container consisting of three parts that are mechanically interlocked by the act of assembling them.

Still another object of the invention is the provision of a shipping container having a plain cover or lid that will not be marred when the container is opened and provides a large plain printing surface.

These and other objects of the invention will become apparent from a consideration of the accompanying drawings constituting a part hereof in which like reference characters designate like parts and in which:

Fig. 1 is a top plan view of a blank cut out to form interlocking side flanges and flaps in accordance with the principles of this invention;

Fig. 2 a top plan view of the blank of Fig. 1 with the side flanges turned over;

Fig. 3 a similar view with the side and end flanges folded to their upright position;

Fig. 4 a top plan view illustrating the interlocking of the side flanges by the folding flaps;

Fig. 5 a vertical cross-sectional view taken along the lines 5—5 of Fig. 3;

Fig. 6 a similar view taken along the line 6—6, Fig. 4;

Fig. 7 a view in perspective of the folded tray;

Fig. 8 a view in perspective of a container body;

Fig. 9 a view in perspective of a collar;

Fig. 10 an exploded view of the tray, the body portion and collar which constitutes the three elements of the container assembly;

Fig. 11 a vertical section partially broken away of the assembled container; and

Fig. 12 an end elevational view of the assembled and closed container.

With reference to Figs. 1 to 7 of the drawings, the structure therein illustrated comprises a blank of corrugated material generally designated by the reference numeral 1, having cutouts 2 and 3 and slots 4. The blank 1 is folded along the dotted lines 5 to form flanges 6 and 7 and the ends are folded along the dotted lines 8 at right angles to the side flanges 6 and 7 to form the flaps or end flanges 9, as shown in Fig. 2.

The end pieces are folded along the dotted lines 10 and 11 to form the end flanges 12 and 13 of Fig. 3 and flaps 14 are folded over the turned-in portions of the side flanges 9 as shown in Fig. 4 with the tongues 15 extending into the slots 4 of the base.

When the end flanges 12 and 13 are folded over with the flaps 14 interlocked by the slots and tongues 4 and 15, respectively, the center flaps 16 will stand vertically, as shown in Fig. 6.

Fig. 7 illustrates the completed tray ready for assembly with the main body and collar of the container.

In Fig. 8 the numeral 17 designates a body portion of corrugated material of a dimension to fit the inner dimensions of the flanges 6, 7, 12 and 13 of the tray of Fig. 7. The end walls are provided with slots 18 spaced from the bottom edge so that the bottom of the slot will be at the level of the top edge of the flanges 12 and 13 when the body is placed in the tray. The bottom of the body 17 is opened and the top is provided with cover flaps 19, 20, 21 and 22, more clearly shown in Fig. 10.

Fig. 9 illustrates a collar designated by the numeral 23 having slots 24 in the end walls thereof spaced from the bottom edge to the level of the tray flanges 12 and 13. The tray 6, the body 17 and the collar 23 are assembled as shown in Fig. 10 by placing the body 17 in the tray to seat on the bottom thereof.

The upstanding flaps are then inserted through the end slots 18 as shown in Fig. 11 and the collar 23 is pressed downward to displace the flaps 16 against the walls of the body 17 as shown by the dotted lines in Fig. 11. When the collar 23 is forced down on the lugs 16 and seated on the bottom of the tray 6, the tray is mechanically interlocked with the main body 17 and the collar 23 is snugly held by its crimping engagement with the lug 16 and its frictional contact with the walls of the body 17.

The container is then ready for packing and the cover flaps 19, 20, 21 and 22 are folded over as shown in Fig. 8, and sealed by staples or tape. The container is then turned upside down as shown in Fig. 12 and the tray 6 becomes the lid or cover of the container, which is sealed and locked. To open the container it is only necessary to cut through one of the lugs 16 to lift one end of the cover, which remains hinged on the un-cut lug 16 at the opposite end.

This is especially practical if the container is used for shipping fruit, such as apples, which is ⁵⁵inspected in transit. Because of the construc-

tion of the cover, the top 25 makes a desirable printing surface which is not destroyed or mutilated by the opening of the cover.

It is evident from the foregoing description of my invention that a shipping container made in accordance therewith provides a strong durable interlocked construction which may be produced in any square, or other rectangular, shapes.

Such containers may be employed for a great many uses and are especially adapted for packing and shipping fruit, eggs, canned goods and the like. The slots in the end walls of the container provide finger grips for handling and the shape of the containers permits of compact storing and shipping.

Although one embodiment of the invention has been herein illustrated and described, it will be evident to those skilled in the art that various modifications may be made in the details of construction or that the containers may be made of other materials than herein specified without departing from the principles herein set forth.

I claim:

1. A container of the type described comprising a blank sheet of material having parallel slots spaced from opposite ends thereof and having the sides bent at right angles, the ends of the blank being slit to form integral flaps, some of which are bent around inturned ends of the sides and interlocked with the slots of the blank

to constitute a self sustaining tray having flanged sides with integral flaps, a main container body seated in said tray having slots for receiving some of the flaps of the tray, and a collar disposed within said main body, said collar being of the inner dimensions of said main container for displacing said flaps downwardly when seated in said tray to interlock the tray with the body of the container, said body having side and end flaps which when folded hold the collar in the container and close the same to form the bottom of the container.

2. A container of the type described comprising a blank of sheet material having parallel slots spaced from opposite ends thereof and having the sides bent at right angles, the ends of the blank being slit to form integral flaps, some of which are bent around in-turned ends of the sides and interlocked with the slots of the blank

15 to constitute a self-sustaining tray-shaped element, a main container body seated in said tray within the flange thereof, said body having slots at the edge of the tray flange for receiving some of the integral flaps of the tray, and a collar

20 disposed within the body to reinforce the side walls thereof, said collar displacing the tray flaps against the walls of the body to interlock the tray and body, and said main container body having cover flaps for closing the open end of the

25 container when packed.

JOSEPH B. ARBUTHNOT.
